UNITED STATES PATENT OFFICE.

JOHN WELLS, OF CAIRO, EGYPT.

GAS-PRODUCER FOR MECHANICAL TRACTION.

1,367,445.

Specification of Letters Patent.

Patented Feb. 1, 1921.

Application filed September 30, 1919. Serial No. 327,441.

To all whom it may concern:

Be it known that I, JOHN WELLS, a subject of the King of Great Britain, of 36 Sharia Falaki, in the city of Cairo, Egypt, have invented new and useful Improvements 5 in Gas-Producers for Mechanical Traction, of which the following is a specification.

In the ordinary type of gas producer for use with coke, anthracite and charcoal, the 10 shape of the producer is usually circular, and the producer is provided with a grate, mechanical or fixed, with a water head or vaporizer for the provision of steam or water vapor mingled with the requisite 15 quantity of air.

In order to provide a gas producer suitable for use on motor vehicles for the production of producer or water gas for use as fuel in lieu of petrol or kerosene, I construct 20 a rectangular form of producer and in lieu of the usual grate I provide a water twyer either with or without a grate. In some cases instead of employing a vaporizer head, I depend for the necessary vapor for admix- 25 ture with the necessary air, on the vapor arising from the heat extracted in the cooling of the water twyer.

By the adoption of my form of water twyer, together with a system of air induction by utilizing the exhaust pressure of the 30 engine, I am able to operate my producer either as a suction producer or a pressure producer or a producer operating in equilibrium.

35 In the accompanying drawings:—

Figure 1 is a front elevation,

Fig. 2 is a longitudinal section and

Fig. 3 a plan of a gas producer constructed according to this invention.

40 In the accompanying drawing A is the rectangular body of the producer normally built of wrought steel plates, the side plates being indicated by B, the end plates by E'.

A cover plate C closes the top of the body 45 A and thereon is fitted a hopper D for containing a supply of fuel. At one end of the

producer are provided two water twyers E connected with a double air inlet F, F, further connected with an injector G which in- 50

jector is operated by a jet H, operated from the exhaust of the engine and drawing air in over the surface of water in a tank I, which is connected by pipes J to the water twyers E. The tank I is also provided 55

with an air inlet pipe K drawing hot air

from the first of the gas coolers (not shown in the drawing). The feed hopper D is fitted with a rod and a conical feed cone L operated from the top of the hopper D by a rod M and the hopper D is also provided 60 with a feed door N for the admission of fuel when the hopper is empty.

In the base of the body A there is provided a grate or shutter O together with a discharge door P for the discharge of ashes. 65 On the distributor piece F is a connection Q of a fan providing the air necessary for starting the producer before the engine commences to operate and provide the necessary pressure in the injector H for the requisite 70 supply of air from the water twyers E. The gas offtake is provided at R through which the gas provided in the producer is led to suitable cooling and cleaning apparatus (not shown in the drawing) before being 75 led to the engine. The shell or body A is provided with a fire brick lining S and with a fire or cleaning door T.

Having now briefly described the general construction of my proposed gas generator 80 for the provision of gas to engines or motor lorries, cars and tractors, I will describe the general operation thereof.

The water twyers E and E having been fitted in position and coupled up with the 85 air and vapor surface injector H and the tank I and having been properly filled with water, a layer of ashes is laid on the grate or slide O up to and approaching the air holes in the twyer irons, and a fire is lighted. 90 The fan attached to Q is now put into operation and at a point on the gas takeoff R an opening is made to the atmosphere, then by operating the fan attached at Q, a current of air is made to pass from the two 95 twyers to the interior of the producer and as the fire becomes well alight the producer is filled full up to the bottom of the cone U. In a few minutes the conditions of the producer are such as to produce ordinary so 100 called producer gas.

The gas outlet R heretofore open to air is closed and the gas allowed to pass from the gas cooling and cleaning apparatus to the engine. As soon as the engine is started 105 up the bypass from the exhaust thereof to the injector H is opened and the producer now operates under (i) suction from the engine or (ii) under pressure due to the injector connection of the injector H. Here- 110

after the producer may be regulated in regard to the production of gas by the pressure created by the opening of the exhaust bypass.

5 As the producer becomes hot and the water in the twyer irons heats up, vapor is created in the tank I and this vapor mixed with the hot air incoming at K is forced by the injector H from the branch pipe F to the two 10 twyer irons according to the richness and quantity of gas required for the proper functioning of the engine. The hopper D in the meantime is charged and the valve L opened so that the fuel from the hopper D passes 15 automatically into the body of the furnace or producer in proportion to the rapidity with which the fuel therein is used. For the purpose of stopping the producer the injector H is put out of action by cutting off 20 the supply of pressure from the engine exhaust and a suitable valve on the gas offtake R is opened to permit free passage of the gas into the air.

25 The twyers are for supplying air for supporting combustion, and to prevent over-heating they are cooled with the aid of water. The water which has thus become heated rises into the tank and the vapor which is produced by the heated water is mixed with 30 the air supply.

35 In the operation of the producer the clearance of ashes is effected by movement of the slide or grate O allowing the ashes to pass into the ash hopper V, the discharge from thence being effected by the opening of the door, P.

What I claim as my invention and desire to secure by Letters Patent is:—

40 1. For use on a self-propelled vehicle, a gas producer comprising a producer chamber, water cooled twyers at the base of said chamber, an air supply pipe to said twyers, a tank for supplying water to cool said twyers, means for circulating water between 45 said tank and around said twyers, an air inlet to said tank above the water level, and means for opening and closing communica-

tion between the air space in said tank and the air supply pipe, substantially as herein described.

50 2. For use on a self-propelled vehicle, a gas producer comprising a producer chamber, oppositely disposed rows of twyers at the base of said chamber, a breeches pipe for conveying air to said rows of twyers, a valve-controlled air inlet in said breeches pipe, a tank for supplying water to cool said twyers, means for circulating water between said tank and around said twyers, an air inlet to said tank above the water level, a pipe 55 connection between the air space in said tank and said breeches pipe, and an injector in said pipe connection, substantially as herein described.

3. For use on a self-propelled vehicle, a gas producer comprising a producer chamber, a slidable grate at the bottom of said chamber, water cooled twyers at the base of said chamber, an air supply pipe to said twyers, a tank for supplying water to cool 60 said twyers, means for circulating water between said tank and around said twyers, an air inlet to said tank above the water level, and means for opening and closing communication between the air space in said 65 tank and the air supply pipe, substantially as herein described.

4. In a gas producer for use on a self-propelled vehicle, the combination with a producer chamber having a slidable grate at 70 the bottom thereof, a fuel hopper at the top thereof and valve controlled means for supplying fuel from said hopper to said chamber, of water cooled twyers at the base of said chamber, an air supply pipe to said 75 twyers, a tank for supplying water to cool said twyers, means for circulating water between said tank and around said twyers, an air inlet to said tank above the water level, and means for opening and closing communication between the air space in said 80 tank and the air supply pipe, substantially as herein described.

JOHN WELLS.
